LOVE SEAT BED AND PILLOW REST
THEREFOR

Peter P. Bebry, Jamaica, N. Y., assignor to Bebry
Bedding Corporation, Bayonne, N. J., a corpora-
tion of New York

Application February 28, 1950, Serial No. 146,849

2 Claims. (Cl. 5—13)

1

This invention relates to an article of furniture which is adapted for use as a love seat, chair, couch and the like and which may be converted into a bed.

The invention has particular reference to an improvement which provides a pillow rest when the article of furniture is employed as a bed and which retains the upper end of the mattress in upwardly projecting relation when the article of furniture is in couch or seat forming relation.

Another object of the invention is to provide a foldable frame adapted to be respectively disposed in bed forming and seat forming relations and to which a cross member is swingably connected for movement from upwardly disposed angular relation forming a pillow rest when the frame is in bed forming condition to depending relation for retaining the mattress in folded position when the frame is in collapsed or seat forming condition.

With the foregoing and other objects in view, reference is now made to the following specification and accompanying drawings in which the preferred embodiment of the invention is illustrated.

In the drawings:

Fig. 1 is a top plan view of an article of furniture provided with a foldable frame constructed in accordance with the invention and illustrating the same in extended bed forming relation.

Fig. 2 is a side view of the frame with portions of the furniture frame shown in vertical section.

Fig. 3 is a fragmentary vertical sectional view taken approximately on line 3—3 of Fig. 2.

Fig. 4 is an enlarged fragmentary side view of the inner portion of the frame with a portion of the furniture frame shown in section.

Fig. 5 is a side view of the frame shown in fully folded condition within the love seat, chair, couch and the like and with the latter shown in vertical section.

In the embodiment of the invention illustrated in the drawings, the article of furniture shown therein is a love seat but which may be a chair, couch and the like. Pivots connected to the opposite sides of the rigid frame A of the love seat, chair, couch and the like is a foldable metal frame 10 consisting of a plurality of hinged connected sections which are adapted to be disposed in aligned relation for supporting a mattress so as to serve as a bed and which are adapted to be disposed in collapsed relation within the confines of the furniture frame to constitute a support for seat cushions so as to serve as a love seat. As illustrated the foldable frame

consists of four sections, namely, an inner end section 11, an intermediate section 12, a connecting section 13 and an outer end section 14 each of which is of angle iron construction consisting of a vertical flange and a horizontal flange extending inwardly from the lower edge of the vertical flange.

The foldable frame 10 also includes a cross member 15 which is pivotally connected with one 10 of the sections for movement therewith from inclined relation forming a pillow rest when the sections are arranged in bed forming condition to depending relation for retaining the inner end of the mattress in upwardly disposed relation 15 when the sections are in collapsed condition.

The inner end section 11 consists of spaced parallel side rails 17 and 18 which are connected together at the inner ends thereof by an angle bar 19. The side rails are pivotally connected 20 at their outer ends to oppositely disposed side rails 20 and 21 of the intermediate section 12 by pivot pins 22 extending through the vertical flanges thereof and with the vertical flanges of the side rails 17 and 18 of the inner end section 11 arranged within the vertical flanges of the side rails 20 and 21 of the intermediate section 12. The inner end section 11 is supported by the furniture frame for pivotal swinging movement by means of upwardly extending arms 23 pivoted 25 at their lower ends to the vertical flanges of the side rails 17 and 18 on pivot pins 24 and pivoted at their upper ends to the upper ends of flat bars 25 on pivot pins 26 which bars are bolted or otherwise secured to the inner faces of the side 30 panels 27 and 28 of the furniture frame. Links 29 are pivoted at their inner ends to the arms 23 on pivot pins 30 and at their outer ends the said links are pivoted to the projecting ends of the vertical flanges of the side rails 20 and 21 of the intermediate section 12 on pivot pins 31.

The side rails 20 and 21 of the intermediate section 12 are pivotally connected at their outer ends to the vertical flanges of the side rails 33 and 34 of the connecting section 13 on pivot pins 35 with the vertical flanges of the intermediate section disposed outwardly of the vertical flanges of the connecting section 13. The outer ends of the side rails 33 and 34 of the connecting section 13 are pivotally connected to the side rails 36 45 and 37 of the outer end section 14 on pivot pins 38 extending through the vertical flanges thereof and which sections are arranged with the vertical flanges of the outer end section 14 disposed outwardly of the vertical flanges of the connecting 50 section 13. The side rails 36 and 37 of the outer

end section 14 are connected together by suitable cross bars at the outer ends thereof.

A wire mesh spring 41 of any desired construction is connected with and stretched between the inwardly directed flanges of the side rails and end bars of the foldable frame 10 for supporting a mattress M when in extended bed forming relation and which spring is adapted to fold with the folding of the sections into collapsed condition within the furniture frame and to retain the mattress M in folded relation between the sections with the upper end of the mattress extending upwardly at the inner end of the inner end section 11.

In order to rigidly support the foldable frame when in extended bed forming relation, two pairs of legs 43 and 44 are provided which are respectively connected with the intermediate section 12 and the outer end section 14 adjacent their outer ends. The upper ends of the legs 43 are pivoted on pivot pins 45 to lugs 46 rigidly secured to and depending from the side rails 20 and 21 of the intermediate section 12. A cross bar 47 extends between the legs 43 and is secured to the inwardly directed flanges thereof.

The legs 44 consist of flat bars which are pivoted to the side rails 36 and 37 of the outer end section 14 on pivot pins 48 extending through the vertical flanges thereof. The legs 44 project above the outer end section 14 and terminate in forwardly directed upper ends 49 to which the outer ends of links 50 are pivotally connected on pivot pins 51 with the inner ends of the links pivotally connected with the side rails 33 and 34 respectively of the connecting section 13 on pivot pins 52. The side rails 36 and 37 of the outer end section 14 are provided with outwardly projecting pins 53 adapted to engage in notches 54 in the inner longitudinal edges of the legs 44 when the legs are in collapsed relation with the frame for limiting the collapsing movement of said legs.

The legs 43 are braced by diagonally extending bars 56 which are pivotally connected thereto substantially medially thereof on pivot pins 57 and at their upper ends the said bars are pivotally connected to the outer ends of bent bars 58 on pivot pins 59. The said bars 58 are pivotally connected to the outer faces of the side rails 20 and 21 respectively of the intermediate section 12 on pivot pins 60 and have their inner ends rigidly affixed to short bars 61. The short bars 61 are pivoted to the inner faces of the side panels 27 and 28 of the furniture frame on pivot pins 62 and the same are tensioned by coiled contractile springs 63 secured at their inner ends to lugs 64 pivoted on pivot pins 65 to brackets 66 secured to the inside faces of said side panels 27 and 28 respectively. The outer ends of the springs 63 are secured to lugs 67 pivoted on pivot pins 68 to the free ends of the short bars 61. The springs 63 are in stretched tensioned condition when the sections of the foldable frame are in collapsed relation with the furniture frame and function to facilitate movement thereof from a lowered collapsed condition within the furniture frame to an elevated relation in which the sections are arranged in aligned bed forming relation.

In order to connect the sections together for effecting collapsing thereof within the confines of the furniture frame by the upward swinging movement of the outer end section 14, a pair of angulated links 70 and 71 is arranged at each side of the foldable frame, the links 70 being

pivoted against the outer faces of the vertical flanges of the side rails 20 and 21 respectively of the intermediate section 12 on pivot pins 72, while the links 71 are pivoted against the outer faces of the vertical flanges of the side rails 33 and 34 respectively of the connecting section 13 on the pivot pins 52. The links 71 are connected at their inner ends with the links 70 intermediate the ends thereof on pivot pins 73 and the said links 70 are formed with rectangular notches 74 in the upper edges thereof adjacent their outer ends. Links 75 are also provided at each side of the foldable frame which are pivoted at their outer ends against the inside faces of the vertical flanges of the side rails 20 and 21 respectively on pivot pins 76. The inner ends of said links are provided with headed pins 77 which slidably protrude through slots 78 in the vertical flanges of the side rails 20 and 21 respectively of the intermediate section 12, the enlarged heads at the outer ends of said pins retaining the same in engagement in said slots and which links 75 limit the folding of the connecting section 13 into right angular relation with the intermediate section 12 as shown in Fig. 5 by the engagement of the headed pins 77 against the ends of the slots 78.

The cross member 15 is rigidly affixed at its ends to end members 93 which are pivoted at their lower ends on pivot pins 94 to the upper ends of the plates 95 riveted or otherwise secured to the vertical flanges of the side rails 17 and 18 of the inner end section 11. Links 96 are pivotally connected at their inner ends to the end members 93 on pivot pins 97 and at their outer ends the said links are pivotally connected to the projecting ends of the vertical flanges of the side rails 20 and 21 of the intermediate section 12 on the pivot pins 31.

This disposes the cross member 15 in inclined relation toward the back of the article of furniture when the collapsible frame 10 is disposed in bed forming condition and with the cross member spaced above the frame for accommodating the forward end of the mattress M therebeneath.

In moving the foldable frame 10 from an extended bed forming relation to a collapsed condition within the furniture frame, the outer end section 14 is swung upwardly on its pivotal connection with the connecting section 13. The upward swinging movement thereof causes the legs 44 to swing inwardly about their pivotal connection with said section so that the legs are swung into substantially parallel relation therewith to dispose the notches 54 in engagement with the pins 53 to thereby prevent further inward collapsing movement of said legs. The outer end section 14 is then moved inwardly to rock the connecting section 13 on its pivotal connection with the intermediate section 12. This raises the links 75 from aligned position with the sections to an angular position and when the headed pins 77 of the links 75 engage against the inner ends of the slots 78, the connecting section 13 will be disposed in right angular relation to the intermediate section 12 and the outer end section 14 will be parallel with the intermediate section 12. The intermediate section 12 is then tilted into an inclined position and swung inwardly and downwardly about its pivotal connection with the inner end section 11 to dispose the said inner end section 11 in vertical relation as illustrated in Fig. 5 of the drawings. This movement of the intermediate section 12 causes

the bent bars 58 to rock about the pivot pins 60 and the short bars 61 to rock about the pivot pins 62 whereby the intermediate section 12 is located within the furniture frame at the rear of the front panel 106.

Swinging of the intermediate section 12 about its pivotal connection with the inner end section 11 lowers the three outer sections to the position shown in Fig. 5 whereby the outer end section 14 is at the proper elevation for receiving seat cushions S shown in broken line in Fig. 5 for use as a love seat or the like. The mattress M folds with the foldable frame 10 to dispose the outer section of the mattress in doubled relation upon the inner section thereof and with the inner end of the inner section moved to an upwardly extending position within the back of the furniture frame. This movement of the inner end section 11 and the intermediate section 12 swings the cross member 15 from the inclined relation shown in Fig. 1 of the drawings to the depending relation shown in Fig. 5 of the drawings. As the mattress M is being moved to the position shown in Fig. 5 of the drawings, the cross member 15 swings downwardly thereagainst to retain the upwardly directed portion between the same and the inner end portion of the wire mesh spring 41 and with the upper end of the mattress abutting against a cross head 107. The cross head 107 is secured to the angle bar 19 at the inner end of the inner end section 11 to form a head or stop for the inner end of the mattress.

What is claimed is:

1. In an article of furniture of the character described, a furniture frame, a foldable seat and bed forming frame composed of an inner end section, an intermediate section, a connecting section and an outer end section, means pivotally connecting said sections together in end to end relation, means swingably connecting said inner end section to the furniture frame for movement of the foldable frame from a collapsed folded condition within the furniture frame in which the inner end section is in upright relation to an extended condition in which the sections are arranged in end to end bed forming relation, side members rigidly affixed to the opposite sides of said inner end section in spaced relation from the inner end thereof and extending upwardly therefrom when the sections are in bed forming relation, a frame including end members and a cross member affixed to said end members, said end members being pivotally connected to said side members respectively in spaced relation with reference to said inner end section for receiving under said cross member a mattress disposed in supported relation on said foldable frame, and links pivotally connected with said intermediate section and with said end members for swinging movement of the last mentioned frame from upstanding relation to constitute a

pillow rest when the foldable frame is disposed in bed forming relation to a substantially right angular relation with the side members to dispose the cross member against the mattress when the inner end section is moved to said upright relation by the movement of the foldable frame into seat forming relation.

2. In an article of furniture of the character described, a furniture frame, a foldable seat and bed forming frame composed of an inner end section, an intermediate section, a connecting section and an outer end section, means pivotally connecting said sections together in end to end relation, means swingably connecting said inner end section to the furniture frame for movement of the foldable frame from a collapsed folded condition within the furniture frame in which the inner end section is in upright relation to an extended condition in which the sections are arranged in end to end bed forming relation, side members rigidly affixed to the opposite sides of said inner end section in spaced relation from the inner end thereof and extending upwardly therefrom when the sections are in bed forming relation, a frame including end members and a cross member affixed to said end members, said end members being pivotally connected to said side members respectively in spaced relation with reference to said inner end section for receiving under said cross member a mattress disposed in supported relation on said foldable frame, said intermediate section including side rails having free inner ends extending inwardly beyond the pivotal connection of said section with said inner end section, and links pivotally connected with said free inner ends and with said end members for swinging movement of the last mentioned frame from upstanding relation to constitute a pillow rest when the foldable frame is disposed in bed forming relation to a substantially right angular relation with the side members and in substantially parallel relation with said inner end section to dispose the cross member against the mattress when the inner end section is moved to said upright relation by the movement of the foldable frame into seat forming relation.
